UNITED STATES PATENT OFFICE.

CHARLES L. TRAVIS, OF MINNEAPOLIS, MINNESOTA.

ATOMIZER.

SPECIFICATION forming part of Letters Patent No. 551,938, dated December 24, 1895.

Application filed August 5, 1895. Serial No. 558,205. (No model.)

To all whom it may concern:

Be it known that I, CHARLES L. TRAVIS, of the city of Minneapolis, county of Hennepin, State of Minnesota, have invented a certain 5 new and useful Improvement in Atomizers, of which the following is a specification.

My invention relates to hose-nozzles, and particularly to a spraying-nozzle.

The object of my invention is to provide a 10 nozzle which will emit a perfectly even and complete cone of spray, and one in which the body or thickness of the spray may be regulated at will and in accordance with the pressure of water at hand.

15 A further object of my invention is to provide a safety-valve whereby bursting of the hose from extreme pressures may be avoided.

To this end my invention consists in the combination, with the nozzle proper, of a conical 20 button or stopper for the end thereof, said button being capable of longitudinal movement, and a spring to act upon said button and against which the pressure of the water must operate to force the button slightly away 25 from the end of the nozzle.

My invention consists further in particular means for holding the button or cone and for adjusting the tension of the spring against the same.

30 The invention will be more readily understood by reference to the accompanying drawings, forming part of this specification, and in which—

Figure 1 is a side view of a nozzle embodying my invention. Fig. 2 is a longitudinal section thereof.

As shown in the drawings, the nozzle proper 2 may be of any desired form and adapted to be coupled upon the hose or pipe 3. The 40 opening within the nozzle is tapered or flared at the outer end to receive the button or cone 4, which, however, is of the form of a more abrupt cone than the opening at the end of the nozzle, so that the cone does not seat firmly 45 in the same.

5 represents a fixed stem having its lower end secured in a bridge or cross-piece 6 within the nozzle. The outer end of the stem or rod 5 is threaded to receive the thumb-nut 6, having a long and round shank 7 which serves as a guide for the cone or button 4, which part is provided with the recess 8 to

receive the part 7 of the thumb-nut. The opening in the inner end of the cone is of greater size than the rod, so that the cone 55 will not bind upon the rod, and between the inner shoulder of the part 4 and the end of the nut I provide a small spring 9, the tension of which is adjustable by means of the thumb-nut 6. The pressure of water within the nozzle will act to force the cone outwardly away from its seat upon the end of the nozzle, and the water will jet or spray in a thin and widely-expanded cone of spray. The distance to which the water is thrown and the fineness of 65 the spray may be regulated by the pressure of the spring 9. The device is entirely automatic in its action, and a constant and even spray may be maintained regardless of the pressure of water. Further, the device acts 70 as a complete safety-valve upon the hose and all liability of the hose bursting is avoided.

A further advantage of my device lies in the ease of adjustment, and further in the small compass of the spray attachment or device, and in the general cheapness of the nozzle in manufacture.

Having thus described my invention, I claim as new and desire to secure by Letters Patent—

1. The combination, with the nozzle, of a central stem or rod, with a cone or button movable thereon and adapted to normally close the end of the nozzle, an adjustable part upon the outer end of said rod, and a spring 85 interposed between said part and said cone or button, substantially as described.

2. The combination, with the nozzle, of a central stem or rod having a threaded outer end, with a cone or button movable thereon and adapted to normally close the end of the nozzle, an adjustable nut upon the outer end of said rod, and a spring interposed between said nut and said cone or button, substantially as described.

3. A nozzle, having a conical opening at its outer end, the cone to close said opening, the central stem whereon said cone is freely movable, said stem having a threaded outer end, a nut adjustable upon said end and having 100 a guide part or shank, whereby said cone is held in position, and a spring interposed between said nut and said cone, substantially as described.

4. The combination, with the nozzle, of a rod fixed in the interior thereof, a conical plug working loosely on said rod and extending out beyond the throat of the nozzle, and an 5 adjustable spring connected with said plug whereby water is ejected from the nozzle in an unbroken conical sheet, for the purpose specified.

5. The combination, with the nozzle, of a rod 10 centrally arranged therein, a conical plug arranged upon said rod and extending out beyond the throat of the nozzle, an adjustable

nut on the end of said rod, and a spring arranged between said nut and said plug, whereby the plug may be regulated according to the pressure of the water in the nozzle, substantially as described. 15

In testimony whereof I have hereunto set my hand this 31st day of July, A. D. 1895.

CHARLES L. TRAVIS.

In presence of—

A. C. PAUL,
FREDERICK S. LYON.
